FIG. 4.

UNITED STATES PATENT OFFICE.

OSCAR F. WESTENHISER, OF ST. LOUIS, MISSOURI.

SHOE-SOLE-PRESS ATTACHMENT.

1,160,479.

Specification of Letters Patent. Patented Nov. 16, 1915.

Application filed December 5, 1914. Serial No. 875,669.

To all whom it may concern:

Be it known that I, OSCAR F. WESTENHISER, a citizen of the United States, residing at St. Louis, State of Missouri, have invented certain new and useful Improvements in Shoe-Sole-Press Attachments, of which the following is a full, clear, and exact description, reference being had to the accompanying drawings, forming a part hereof.

My invention has relation to improvements in shoe-sole press attachments, and it consists in the novel features more fully set forth in the specification and pointed out in the claims.

In the drawings, Figure 1 is a side elevation of a shoe-sole press with my attachment in position; Fig. 2 is a top plan of the platform of the press with my attachment in position and shown applied to a stack of shoe soles ready to be pressed, the fixed member of the press being shown in cross-section; and the movable member being removed; Fig. 3 is a vertical cross-section on the line 3—3 of Fig. 1; and Fig. 4 is a perspective detail of the looped anchor for attaching one end of the cord which is passed around the stock deposited on the platform.

The present device serves as an attachment to shoe-sole presses on the order of that for which U. S. Letters Patent issued to myself and William P. Jones, numbered 1,098,699, dated June 2, 1914, and has for its object to provide means whereby the sole layers with their "slips" may be secured and held against displacement when once deposited and properly stacked on the platform of the press and before the plunger or follower of the press begins to descend on and compress the layers of soles so stacked.

A further object is to provide securing means which are simple and readily applied, as fully apparent from a detailed description of the invention, which is as follows:

Referring to the drawings, 1 represents the fixed or stationary member or section of the press, 2 the movable or adjustable section or member, 3 the plunger or follower carried by the adjustable member, the necessary play being accorded to said follower by the loops or staples 4, all as fully shown in the patent press aforesaid, the follower in the present instance being actuated

however by a cam-lever 5 mounted on the upper cross-bar of the member 2 in lieu of the press-screw shown in the patent.

P represents a platform at the base of the fixed member or section of the press on which the out-soles S and their slips s to be cemented are deposited, it being of course desirable, after the several sole and slip layers are properly stacked on the platform, that no displacement thereof takes place prior to and pending the descent of the follower 3 thereon. The means employed herein to hold the stacked soles against displacement are as follows: Secured at two points on one side of the platform at suitable distances from the staff or fixed section 1 of the press are securing nails or screws 6, 6, to each of which is permanently attached one end of a stout cord a, there being disposed on the opposite side of the platform and diametrically opposite the screws 6, 6, suitable anchors 7, 7, formed of two or more resilient contiguous coils or loops, from the outer members of which extend arms 8, 8, in opposite directions, the free ends of the arms terminating in eyes 9, 9, for the reception of the stems of suitable fastening nails or screws 10 by which the anchors are secured to the platform.

In actual operation, after the soles with their slips have been stacked on the platform P, and before the adjustable section 2 with its follower 3 has been lowered to bring the follower into contact with the upper sole of the stack, the operator passes the cords a around the stacks, pulling the cords taut and passing the free ends thereof between one of the arms 8 and the adjacent coil or between two contiguous coils of the anchors 7, the friction of the coils or coil and arm between which the cord is passed holding the cord against slipping, so that each stack is held against displacement pending the forcing of the follower 3 down upon it, which presses the soles and their slips together and causes the cement or adhesive between them to adhere. After the pressure of the follower has been removed, the cords a are unfastened from their respective anchors by seizing the free ends of the cords and drawing them out from between the anchor members between which they are gripped, the stack of soles with the slips cemented thereto being re-

moved from the platform, leaving the platform clear for the deposit of a fresh lot of soles or equivalent stock.

In practice, a single cord for holding one stack is usually sufficient, although I do not wish to be restricted to any particular number of cords for any stack. The term "cord" is to be taken in its broadest sense and means any cord, cable, chain, band, or equivalent flexible member adapted to be passed around the stock deposited on the platform.

Having described my invention, what I claim is:

- 15 1. In combination with a platform for supporting suitable stock to be operated on, a cord secured at one end on one side of the platform and of a length sufficient to be passed around the stock, and a resilient anchor on the opposite side of the platform for frictionally and detachably securing the opposite end of the cord thereto.
- 20 2. In combination with a platform for supporting suitable stock to be operated on, a cord secured at one end on one side of the platform and of a length sufficient to be passed around the stock, and an anchor pro-

vided with a series of resilient coils or loops between any pair of which the free end of the cord may be passed and held against 30 slipping.

3. An anchoring attachment for press platforms comprising a member having two or more contiguous resilient loops between which a cord or band may be passed, and 35 arms extending from the outer loops in opposite directions, and secured to a fixed support.

4. An anchoring attachment for press platforms comprising a member having two 40 or more contiguous resilient loops between which a cord or band may be passed and held frictionally against slipping between contiguous loops, arms extending in opposite directions from the outer loops of the 45 series, said arms terminating in eyes for the passage of securing nails or screws.

In testimony whereof I affix my signature, in presence of two witnesses.

OSCAR F. WESTENHISER
